UNITED STATES PATENT OFFICE.

THOMAS J. HAMMOND, OF NEW YORK, N. Y.

WRENCH.

No. 907,346.

Specification of Letters Patent.

Patented Dec. 22, 1908.

Application filed June 5, 1908. Serial No. 436,904.

To all whom it may concern:

Be it known that I, THOMAS J. HAMMOND, a citizen of the United States, residing at New York, in the county and State of New York, have invented a new and useful Improvement in Wrenches, of which the following is a specification.

This invention relates to a wrench having a fixed and a slidable jaw, and the object of the invention is to provide means for automatically locking the sliding jaw against rearward movement as soon as it comes in contact with a pipe, nut, or other object to be gripped.

15 The invention consists in the novel features of construction hereinafter described, pointed out in the claims and shown in the accompanying drawings, in which—

Figure 1 is a side elevation of the wrench. Fig. 2 is a longitudinal, vertical section. Fig. 3 is a longitudinal, horizontal section. Fig. 4 is a detail section on the line 4—4 of Fig. 1. Fig. 5 is a detail transverse section on the line 5—5 of Fig. 1. Fig. 6 is a detail 20 perspective view, partly in section of a block and pawls carried by said block.

In these drawings 1 represents a slotted shank having a fixed jaw 2 at one end, the slot of the shank being covered by side plates 30 3 also slotted as at 4. A slidable jaw 5 slides freely on the shank 1 and within said jaw and shank is placed a block 6 having a T-shaped slot 6^a arranged vertically and having a rounded head portion. The block is 35 also slotted horizontally and is held in position relative to the sliding jaw 5 by a pin 8, which passes through the horizontal slot 7. Within the shank 1 are placed upper and lower rack bars 9 and to engage these bars I

40 provide upper and lower pawls 10 provided throughout their main body portions with teeth to engage the rack bars and each having at one end a reduced neck portion provided with a cylindrical head 11, which heads rest 45 in the head of the slot 6^a, the pawls moving vertically in said slot. A spring 12 serves to normally hold said pawls away from the rack bars and the adjacent faces of said pawls are recessed as shown at 13 and in said recess fits 50 a wedge-shaped locking member 14 provided with thumb pieces 15 which project

outwardly through the slots 4 of the side plates 3.

In operation the sliding jaw 5 is moved toward the fixed jaw 2 by pressure upon one or both of the thumb pieces 15. As soon as said jaw engages the object to be gripped its sliding movement will cease and the continued pressure upon the thumb pieces 15 will carry the locking member 14 forward out of the recess 13, thus spreading apart the pawls 10 and bringing them into engagement with the rack bars. This will at once lock the sliding jaw against rearward movement, and it will remain locked until rear pressure upon the thumb pieces, or one of them, returns the locking member to its position in the recess 13, when the sliding jaw will also be moved rearward by continued rear movement of the thumb pieces 15. It will be noted therefore 70 that the stoppage of the jaw 5 by contact with a pipe or nut will act to cause the pressure which had previously acted upon said jaw to be applied in moving the locking member out of its normal position, thus locking the jaw in place.

Having thus fully described my invention, what I claim as new and desire to secure by Letters Patent, is:—

1. In a wrench, a slotted shank, a fixed 80 jaw, a slidable jaw, rack bars arranged in the slotted shank, pawls for engagement with said rack bars, said pawls being loosely connected to the sliding jaw, and a wedge-shaped locking member working between said pawls, 85 said locking member moving the sliding jaw into contact with the object to be gripped, and throwing the pawls into engagement with the rack bars upon continued pressure upon said locking member. 90

2. In a wrench, a slotted shank, rack bars carried thereby, a slidable jaw, a vertically slotted block connected to said jaw and working in the slotted shank, pawls for engagement with the rack bars, said pawls being recessed on their adjacent faces, and having head portions resting loosely in the slot of the block, a wedge-shaped locking member resting in the recesses of the pawls, and laterally projecting wings carried by said locking member, as and for the purpose set forth. 95 100

3. In a wrench, a longitudinally slotted shank, upper and lower rack bars arranged in said shank, a fixed jaw on the shank, a jaw sliding on the shank, a vertically slotted block sliding in the shank in unison with the jaw, oppositely arranged pawls provided with teeth to engage the rack bars, their adjacent faces being recessed, an end of each

pawl working in the vertical slot of the block, and a wedge-shaped locking member arranged between said pawls and normally seated in said recesses. 10

THOMAS J. HAMMOND.
